RAIL FLAW DETECTOR MECHANISM

Henry Schumacher, Walter M. Perry, and Loren J. De Lanty, Brooklyn, N. Y., assignors to Sperry Products, Inc., Brooklyn, N. Y., a corporation of New York

Application February 8, 1935, Serial No. 5,534

9 Claims. (Cl. 175—183)

This invention relates to rail flaw detector mechanisms of the type embodied in the Sperry rail flaw detector. The operation of these mechanisms is now well known and consists of a car which operates along the rails and carries a mechanism responsive to internal flaws. When such a flaw is encountered an indication is made upon a chart in the moving car and at the same time marking means such as paint is discharged 10 on the rail in the region of flaw.

It is highly desirable that the marking means should operate quickly in response to energization in order that the mark on the rail may be properly located, and it is further desirable that 15 the mark be limited in extent to substantially the region of a flaw. If the marking means is slow in responding to an impulse it may be that the paint will be placed upon the rail at a point several inches removed from an actual flaw and may 20 be located at a surface defect such as a burn which the operator will misinterpret. Also, if the mark is too long it may be that the said mark originally was made in response to a surface defect but extends along the rail to such a 25 distance that a fissure near a surface defect will be missed since the operator will interpret the mark, no matter how long, as being due to the surface defect.

This invention, therefore, has for its principal 30 object the provision of rail marking means and actuating means therefor which will result in a quick response of the marking means and which will yield a mark of relatively short length.

Further objects and advantages of this invention will become apparent in the following detailed description thereof.

In the accompanying drawings,

Fig. 1 is a side view of a Sperry rail fissure detector car, the main portion of the car being 40 broken away to show the detector mechanism.

Fig. 2 is a view largely in the form of a wiring diagram illustrating one form of our invention.

Figs. 3 to 7 inclusive are views similar to Fig. 2 illustrating modified forms of our invention.

Referring to Fig. 1 of the drawings, there are shown the parts of a standard Sperry rail fissure detector car which includes a car body 10 operating along the rails R. Fissure detection is accomplished by passing current through each 45 rail from a generator G within the car-body supplying current to spaced current brushes 11 and 12 supported upon the current brush carriage 13 which when in lowered or effective position is adapted to ride upon the rail by means such as 50 wheels 15. The current brush carriage 13 is

normally held in elevated or ineffective position by means of springs, not shown, and cables 16, but when it is desired to lower said carriage, fluid pressure such as compressed air is supplied to the cylinders 17 to force out pistons 18 which are pivotally connected at 19 to the current brush carriage 13. The current passed through the rail by way of spaced brushes 11 and 12 will establish an electromagnetic field surrounding the rail and this field will be uniform except in 10 the region of flaw, where it will be distorted. Such distortions of the electromagnetic field are detected by a flaw responsive mechanism which may take the form of a pair of induction coils 22 supported in a housing 23 at a constant distance above the rail surface by means of a carriage 24. Said carriage 24 is mounted on current brush carriage 13 by means of loosely fitting bolts 25 and springs 26 to permit said carriage 24, while riding on the rail on means such as 20 wheels 27, to move independently of carriage 13 so that the said carriage 24 may at all times maintain parallelism with the rail surface regardless of irregularities thereof. The coils 22 normally cut the same number of lines of force, 25 but on entering a region of flaw, first one coil and then the other will cut a different number of lines of force to generate a differential E. M. F. which after being suitably amplified by an amplifier A may be caused to actuate a pen P operating on a chart, not shown. At the same time that pen P is actuated, there is actuated also marking means which may take the form of a paint gun 30 mounted on the current brush carriage 13 a sufficient distance behind the flaw 35 responsive members 22 to compensate for the movement of the car and for the lag in operation of the paint gun.

As stated in the introduction hereto, it is highly desirable that the paint gun be so operated 40 that a relatively short mark will be placed upon the rail in the region of flaw, regardless of the magnitude of the impulse passing through the amplifier A or the length of time that said impulse persists. For this purpose we have provided various forms of our invention, all of which operate upon the same fundamental principle. This principle may be stated briefly as follows: Each time an impulse comes through amplifier A sufficient to operate the recording pen, the paint gun magnet is energized and at the same time there is rendered operative, means for de-energizing the paint magnet; but the deenergization of the paint magnet is delayed for a prede- 50 55

terminated period by means either mechanical or electrical.

In the form of the invention shown in Fig. 2 an impulse from amplifier A in response to flaw 5 energizes magnet 40 to attract armature 41 against the action of spring 42 to close a set of contacts 43 which energizes the pen magnet 44 to actuate pen P and paint gun magnet 50. The energization of magnet 50 is effected as follows: 10 The closing of contacts 43 energizes a magnet 60 which attracts its armature 61 against the action of a spring 62 to break a set of contacts 63 and close contacts 64. The circuit through magnet 60 extends from contacts 43 through 15 battery B, magnet 44, and contacts 63. The closing of contacts 64 closes the circuit through magnet 50 and opens the circuit through magnet 60. The magnet 50 attracts its armature 56 which is an extension of the stem of valve 54 20 which controls the passage of marking fluid from inlet 52 to outlet 53. The attraction of valve stem 56 is against the action of a restoring spring 55.

From the above description it will be seen that 25 at the same time that magnet 50 is energized by the closing of contacts 64 the circuit through magnet 60 is broken by the opening of contacts 63. This would ordinarily tend to cause magnet 60 to release armature 61, thus breaking contacts 64 and deenergizing magnet 50. However, there is connected in parallel with coil 60 a branch circuit 65 so that even when the circuit through coil 60 is broken there is a closed circuit through coil 60 and by-pass 65 wherein the induced current due to breaking the circuit through 30 60 may flow to keep coil 60 energized for a predetermined interval. Coil 60 will thus continue to attract its armature 61, even though the circuit therethrough has been broken at 63, and will 35 continue to maintain coil 50 energized for a predetermined time. This time may be varied by means of an adjustable rheostat 66 in the branch circuit 65.

From the above description it is apparent that at 40 the same time that contacts 64 are closed to energize the paint gun magnet 50 there is rendered effective a means for deenergizing the magnet 50, said means comprising the broken circuit through magnet 60 which tends to release its armature 61 and thus break contacts 64. Said means for deenergizing the magnet 50 is, however, delayed in its action by reason of the inductive circuit 60, 65, 66 whereby a predetermined period of actuation of magnet 50 is obtained at each impulse from amplifier A.

In Fig. 3 we have disclosed another form of our invention embodying the same principle. In this form an impulse from amplifier A energizes magnet 40 to break the set of contacts 43 against 45 the action of restoring spring 42 and thus break the circuit through magnets 67, 68, and pen magnet 44. This causes the pen magnet 44 to release its armature 45 to cause pen P to make a record upon a chart, not shown. The de-magnetization of magnet 68 permits spring 69 connected to the armature 70 to close a set of contacts 71 and energize paint gun magnet 50 as in the Fig. 2 form. In this form of the invention, also, at the same time that magnet 50 is 50 energized there is rendered operative means for deenergizing said magnet, which means, however, is delayed in its action for a predetermined period to permit the paint gun to place a mark of constant length on the rail. This latter means 55 includes the magnet 67 which when deenergized

releases its armature 72 to break contacts 73 which are in the circuit through contacts 71, magnet 50, and battery B. While magnet 67 is deenergized when contacts 43 open, said magnet is a delayed action magnet as compared to magnet 68 which operates quickly and therefore magnet 67 is not deenergized until a predetermined interval has elapsed after the deenergization of magnet 68 and the closing of contacts 71 to energize magnet 50. When this period has elapsed, however, and magnet 67 has become deenergized, contacts 73 open to deenergize magnet 50 and close the paint gun valve 54.

The Fig. 4 form of the invention is similar in part to the Fig. 3 form. In this form an impulse from amplifier A energizes magnet 40 to break contacts 43 and deenergize magnet 68' and pen magnet 44. Magnet 68', being a rapid acting relay which deenergizes quickly, releases its armature 70' to close contacts 71' and energize simultaneously magnet 67' and paint gun magnet 50. The energization of magnet 67' attracts armature 72' to open a set of contacts 73' in the circuit of magnet 50. Here, too, it will be seen that as soon as magnet 50 is energized there is simultaneously rendered operative the magnet 67' which tends to deenergize magnet 50. The characteristics of magnet 67', however, are different from those of magnet 50 so that it takes a longer time for the magnet 67' to become energized sufficiently to attract its armature 72' than it takes coil 50 to attract its armature 56. As a result, the paint gun will be operated for a predetermined interval of time until magnet 67' becomes energized to a sufficient degree to open contacts 73'.

The Figure 5 form of the invention is similar to the Figs. 3 and 4 forms of the invention except that the delay is introduced mechanically instead of electrically. In this form an impulse from amplifier A energizes a coil 40 which opens contacts 43 and deenergizes magnet 68'' and pen magnet 44. The deenergization of magnet 68'' permits spring 69'' to move the armature away from magnet 68''. This armature is of the following construction—it includes a relatively rigid member 75 to which is fixed a light spring member 76 carrying one of a set of contacts 77. As soon as magnet 68'' releases armature 75, 76, contact 77 carried by members 76 engages the other of said contacts 77 carried at the lower end of a pendulum 78 pivoted at 79. Said pendulum has fixed thereto a contact 80 normally in engagement with another contact 80' in the circuit of paint gun magnet 50. As the armature 75 moves to the right in Fig. 5, contacts 77 will close. The spring finger 76 pressing against pendulum 78 is not sufficient to separate contacts 80 and 80' against the action of spring 81 tending to maintain said contacts closed. As soon as contacts 77 are closed, the circuit through magnet 50 is closed and the paint gun operates. The armature 75, however, continues its movement toward the right until a projection 82 carried thereby engages spring finger 76 and thereafter any further movement of armature 75 is sufficient to separate contacts 80, 80' since spring 69'' has the necessary strength to overcome spring 81. It will thus be seen that at the time contacts 77 close to energize magnet 50 there is already in action the means which will break the circuit through said magnet 50, but said means is delayed by the period necessary for spring 69'' to move armature 75 a sufficient distance to cause 75

projection 82 to engage spring member 76 and move pendulum 78 to break contacts 80, 80'.

In the Fig. 6 form of our invention there is disclosed the same principle, the delay being introduced electrically as in the Figs. 2, 3 and 4 forms of the invention. In addition, we provide means whereby the paint gun is given a more definite starting action with respect to the movement of the car, so that the paint mark is more accurately located with respect to the indicated defect. For this purpose, I have shown the output of amplifier A applying the voltage surge across a grid resistance of a gaseous discharge tube such as a Thyratron tube T. The characteristics of the tube are such that it can be tripped at any desired point, which will always be constant relative to the input from amplifier A. Thus, the action of the tube gives a constant starting point for initiating the action of the paint gun. When the tripping point has been reached the tube T will discharge its current by way of the plate circuit through pen magnet 44 and a magnet 60' which in its action is similar to that of magnet 60 in the Fig. 2 form. Said magnet 60' will close contacts 64' to close the circuit through the paint magnet 50 and energize the paint gun as before. However, as soon as magnet 50 is energized by closing of contacts 64', magnet 60' is deenergized by the opening of contacts 63' which breaks the tube circuit and tends to deenergize magnets 44 and 60'. This de-energization of magnet 60' would cause it to release its armature 61' and thus break contacts 64' to deenergize magnet 50. In fact, since contacts 63' are broken even before contacts 64' are made, magnet 60' would tend to be deenergized almost before magnet 50 could be energized. However, the de-energization of magnet 60' is delayed as in the Fig. 2 form by establishing a shunt path 65' which will, upon breaking of the circuit through 60' at 63', tend to induce a current in said circuit 60', 65' to keep magnets 60' energized for a predetermined period and thus maintain contacts 64' closed for a predetermined period to permit magnet 50 to actuate a paint gun valve 54 for a constant interval each time there is a current surge out of tube T.

Figure 7 is a form of the invention similar to Fig. 6 except that provision is made whereby individual paint marks will be obtained in response to impulse in close succession. For this purpose there are employed two gaseous discharge tubes T and T'. When tube T is tripped, the circuit is closed by way of contacts 85 through a circuit control magnet 86, pen magnet 44 and paint gun magnet 87. The energization of magnet 87 will cause an armature 88 to be attracted to close contacts 89 which closes a circuit through paint gun magnet 50. The energization of magnet 86, however, causes it to attract its armature 90 and break the circuit through magnets 44 and 87 by reason of the opening of contacts 85. This would ordinarily tend to deenergize magnet 87 and break the circuit through magnet 50. It will be seen that almost as soon as the tube T trips, magnet 86 is energized to break contacts 85 so that ordinarily the means for breaking the circuit through magnet 50 is rendered operative as soon as the circuit is established through magnet 50. A delay in the breaking of the circuit through magnet 50 is, however, obtained by reason of the shunt path 87' in parallel with magnet 87 as hereinbefore described to prolong the energization of said magnet for a predetermined interval after contacts 85 have opened and thus permit magnet 50 to operate the paint gun for a predetermined

constant interval at each tripping of tube T. In order to render the device effective to respond to a closely succeeding impulse from amplifier A at the time that contacts 85 are opened, we provide the armature 90 with a contact forming one of a set of contacts 91 adapted to be closed when the magnet 86 is energized. This places a second tube T', connected in parallel with tube T, in operative position so that should an impulse come through sufficient to trip tube T' magnets 86, 44 and 87 would again be energized by way of contacts 91 instead of by way of contacts 85.

In accordance with the provisions of the patent statutes, we have herein described the principle and operation of our invention, together with the apparatus which we now consider to represent the best embodiment thereof, but we desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described our invention, what we claim and desire to secure by Letters Patent is:

1. In a rail flaw detector mechanism having means responsive to flaw and marking means, means whereby said responsive means renders said marking means effective, electromagnetic means for rendering said marking means ineffective, and means whereby said responsive means renders said preceding means operative, said electromagnetic means having delayed action characteristics for delaying the action of said means for rendering the marking means ineffective.

2. In a rail flaw detector mechanism having means responsive to flaw and marking means, means whereby said responsive means renders said marking means effective, means for rendering said marking means ineffective, means whereby said responsive means renders said preceding means operative, and means including an inductive circuit for delaying the action of said means for rendering the marking means ineffective.

3. In a rail flaw detector mechanism, means responsive to flaw, marking means, means including a magnet whereby said responsive means renders said marking means effective, means including a magnet for rendering said marking means ineffective, and means whereby said responsive means renders said preceding means operative, said second magnet having a different inductance from said first magnet whereby the action of said means for rendering the marking means ineffective is delayed.

4. In a rail flaw detector mechanism, means responsive to flaw, marking means, means including a magnet whereby said responsive means renders said marking means effective, means including a magnet for rendering said marking means ineffective, and means whereby said responsive means renders said preceding means operative, said second magnet having a greater inductance than said first magnet whereby the action of said means for rendering the marking means ineffective is delayed.

5. In a rail flaw detector mechanism, means responsive to flaw, marking means, means whereby said responsive means renders said marking means effective comprising a movable element, a second movable element for rendering said mark-

ing means ineffective, and means for delaying the action of said second element.

6. In a rail flaw detector mechanism, means responsive to flaw, marking means, a movable member, means whereby said flaw responsive means moves said movable member, said member having means for rendering said marking means effective and delayed action means for rendering said marking means ineffective.

10 7. In a rail flaw detector mechanism having means responsive to flaw and marking means, a gaseous discharge tube having a plate, filament and grid, means whereby said responsive means impresses a voltage on said grid in response to flaw to pass current, means controlled by the plate current of said tube for rendering said marking means effective, said means controlled by the plate current of said tube having means for rendering said marking means ineffective, and means for delaying the action of said means for rendering said marking means ineffective.

15 8. In a rail flaw detector mechanism having means responsive to flaw and marking means, a gaseous discharge tube having a plate, filament and grid, means whereby said responsive means impresses a voltage on said grid in response to

20 flaw to pass plate current, means controlled by the plate current of said tube for rendering said marking means effective, said means controlled by the plate current of said tube having means for rendering said marking means ineffective, and means for rendering the other of said tubes operative when said means controlled by the plate current of the first tube have been rendered effective.

25 marking means effective, said means controlled by the plate current of said tube having means for rendering said marking means ineffective, and means including an inductive circuit for delaying the action of said means for rendering said marking means ineffective.

9. In a rail flaw detector mechanism having means responsive to flaw and a plurality of gaseous discharge tubes, means for rendering one of said tubes operative, each of said tubes having a plate, filament and grid, means whereby said responsive means impresses a voltage on the grid of said operative tube in response to flaw to pass current, means controlled by the plate current of said operative tube for rendering said marking means effective, said means controlled by the plate current of said operative tube having means for rendering said marking means ineffective, means for delaying the action of said means for rendering said marking means ineffective, and means for rendering the other of said tubes operative when said means controlled by the plate current of the first tube have been rendered effective.
